United States Patent Office

Des. 177,485
Patented Apr. 17, 1956

177,485

COIN BANK

John M. Shields, Winamac, Ind., assignor to Chicago
Thrift-Etching Corporation, Chicago, Ill., a corporation of Illinois

Application March 5, 1954, Serial No. 29,370

Term of patent 3½ years

(Cl. D34—11)

FIG. 1

FIG. 2

Fig. 1 is a perspective view of a coin bank embodying my new design; and

Fig. 2 is a side elevation view of the bank.

I claim:

The ornamental design for a coin bank, as shown.
